UNITED STATES PATENT OFFICE.

GILBERT E. ALPHIN, OF NORWOOD, NORTH CAROLINA.

CURTAIN-ROD AND SHADE-ROLLER SUPPORT.

1,345,340.

Specification of Letters Patent.

Patented July 6, 1920.

Application filed November 4, 1919. Serial No. 335,621.

To all whom it may concern:

Be it known that I, GILBERT E. ALPHIN, a citizen of the United States, residing at Norwood, in the county of Stanly and State of North Carolina, have invented certain new and useful Improvements in Curtain-Rods and Shade-Roller Supports; and I do declare the following to be a full, clear, and exact description of the invention, such as will enable others skilled in the art to which it appertains to make and use the same.

This invention relates to curtain-pole and shade-roller supports.

One object of this invention is to generally improve upon devices of this character by providing an improved structure which consists of comparatively few and simple parts, the majority of these parts being formed of springy sheet metal blanks, these parts being held in adjustment by the inherent springiness of certain of the elements of the device; and the spring clamping functions of the respective elements obviating the necessity for use of rivets or similar securing devices, whereby the cost of manufacturing is minimized, and the convenience, utility, efficiency, durability and ornamentality is maximized.

A further object of this invention is to provide a device of this character which can be very quickly and easily adjusted and transformed so as to be attached in different positions to a window and adjusted to fit windows and door-ways of different sizes and forms (including double, triple, and other multiple windows), this device also being useful to support a curtain between windows for utilizing the space between windows for hanging clothes on the wall behind this curtain.

A further object is to provide an improved auxiliary support that is quickly and easily adjusted between windows and adapted to combine with the other supporting elements of this invention for supporting curtains at the windows.

A further object is to provide an improved curtain-bracket in connection with a supporting and connecting strip or bar with which it has spring-pressed frictional or clamping engagement to hold it in different adjustments.

Other objects and advantages may become apparent to persons who read the following details of description in connection with the accompanying drawings in which:

Figure 1 is a view representing a window in horizontal section, my improved supporting device being shown, in top plan, attached to the upper periphery of the window casing.

Fig. 2 is a front elevation of the device illustrated in Fig. 1.

Fig. 3 is a front elevation of the upper portion of a door-way having my improved device attached to the lower surface of the upper part of the door frame.

Fig. 4 is an enlarged vertical sectional view, the section being taken along the line 4-5 of Fig. 2, viewed from the right of said line.

Fig. 5 is a vertical sectional view along the line 4-5 of Fig. 2, viewed from the left of said line.

Fig. 6 is a perspective view of one of the horizontal adjustable curtain supporting brackets.

Fig. 7 is an enlarged perspective view illustrating the outer end of one of the bars which constitutes an element of the horizontal supporting structure on which the member shown in Fig. 6 is adjustably secured.

Fig. 8 is a detail view illustrating a portion of one of the horizontal bars and a portion of the adjustable bracket shown in Fig. 6, the section being taken substantially along the longitudinal center of the supporting bar or strip.

Fig. 9 is a view somewhat similar to Fig. 1, but illustrating the device in combination with an auxiliary support attached to the partition between two windows of a pair.

Fig. 10 is a view illustrating a combination in which two of my improved supporting devices are employed for supporting three curtain-poles or shade-rollers, also combining to support a long curtain-pole which extends throughout the combined horizontal length of the windows.

Fig. 11 is a perspective view illustrating an auxiliary supporting attachment or bracket such as illustrated at the middle lower portion of Fig. 9.

Referring to these drawings in detail, in which similar reference characters correspond with similar parts throughout the several views, and in which the window frames and door frames are typical of ordinary constructions of this character, being shown merely to demonstrate the application, uses

and advantages of my improved curtain supporting device.

The invention comprises, in its simplest form, a pair of supporting bars 1, a pair of 5 supporting brackets 2 and a retractile spring 3 which is preferably of the closed helical type.

Each bar 1 is preferably formed of strap iron or a strip of sheet metal and has one 10 end bent back toward the other end and formed with toothed prongs 4 for penetrating engagement with the periphery of a window casing as illustrated in Figs. 1, 9 and 10, and a slot or notch 5 is provided between the toothed prongs 4 for reception of 15 the headed end of a nail, screw or similar fastening device, as indicated at 5 in Figs. 3 and 7. Each bar 1 is also provided with a series of adjusting apertures 6 (see Figs. 20 2 and 8), and hooks 7 are formed on or secured to the ends of the spring 3, these 25 hooks extending through the apertures 6 and being interchangeable with relation to these apertures to provide a wide range of 30 adjustment so that the device may be quickly and easily adjusted to fit both very narrow and very wide windows. The inner end of 35 each bar 1 is turned at right angles to the major portion to form a laterally extending flange 9, and this flange or ear is provided with a large circular aperture 8 through 40 which the spring 3 extends. It will be seen therefore, that the spring 3 not only draws the bars 1 toward one another so as to retain 45 their engagement with the window frame or with the nail or screw, as indicated in Figs. 1 and 3, but it also supports the inner ends of the bars 1 and holds them in longitudinal alignment with one another. While the 50 holes 6 provide a wide range of adjustment, the spring 3 provides an infinite number of fine and accurate adjustments, and automatically adjusts the length of the device according to the distance between attaching 55 points. Moreover, by engaging the hooks in corresponding apertures of the bars 1, so that the distance between the respective hooks and the apertured flanges is substantially equal, the device presents a symmetrical and ornamental appearance which enhances its value as an article of merchandise. The hooks are turned back toward one another to such extent that they cannot become disengaged from the apertures 6 while 60 the spring is straight, but by deflecting laterally the portion of the spring between a hook and the adjacent flange 9, and then deflecting this portion of the spring in a circular direction around the contiguous bar 1, the hook may be very quickly and easily disengaged from the bar and shifted from one to another of the adjusting apertures 6.

Each curtain bracket is formed integrally of a springy sheet metal blank, this blank being provided with apertures and

notches or recesses for the several purposes hereinafter explained. Referring to Fig. 6, it will be seen that the blank is bent at 10 so as to form 2 parallel arms 11 and 12, and also to form a clamping element 13 which 70 has its edges united with the arms 11 and 12 at 10. Slots 14 are provided at the angular junctions of the elements 13 and the arms 11 and 12, these slots being of a length but slightly greater than the width of the 75 bars 1, but having a width considerably greater than the thickness of the bars 1.

The outer edges 14^a of the slots 14 are disposed slightly inwardly of the plane of the inner surface of the clamping element 13, 80 so that a bar 1 can only be passed through the slots 14 when the arms 11 and 12 are sprung inward toward one another, this 85 springing of the arms 11 and 12 causing the clamping element 13 to move away from the plane of the edges or shoulders 14^a sufficiently to permit the bar 1 to pass through the slot 14. Because of the springiness of the member 2, the arms 11 and 12 will be returned to their normal parallel relation to 90 one another when they are released, and this effects a clamping or binding engagement of the member 2 with the member 1 so that these members are frictionally held in every adjusted relation to one another. In 95 order that the engaging element 13 may be deflected or bent to a greater extent than the arms 11 and 12 when the latter are pressed toward one another, the bracket is provided with notches 15 in its opposite edges, and 100 this also relieves the bent or angular portions 10 from undue strain. Both the arms 11 and 12 are provided with pintle-receiving apertures or bearings 16, 17 and 18, the latter being employed only when the device 105 is used in the relation shown in Fig. 3, that is, when the arms 11 and 12 extend downward instead of horizontally as in Figs. 1 and 2. The apertures 16 are preferably 110 larger than the apertures 17 and are spaced farther from the plate 12 or bases of the arms. This provides for accommodating both large rollers having large pintles and small rollers having small pintles, although the shade-rollers having small pintles may 115 be seated in the relatively large apertures 16 in the event it is desired to space the curtain a greater distance from the window than if it were seated in the bearing 17. The apertures 16 and 17 are elongated for receiving the flat stationary pintle or spring connection of an ordinary shade roller, and the roller may be reversed, this being permitted in consequence of all of the apertures 16 and 17 being elongated, it being 120 obvious that the rotary pintle of the roller can rotate as well in the elongated bearing as in a circular bearing.

In addition to the curtain-supporting apertures or bearings described with regard 130

to the arms 11 and 12, the latter arm is provided with inner and outer circular apertures 19 which are adapted to receive a metal curtain rod or pole of comparatively small diameter, and moreover, two opposite edges of the arm 12 are formed with arcuate notches or seats 20 to receive and support a wooden curtain pole of relatively large diameter. The purpose of two notches 20 is to provide for supporting the curtain-pole when the bracket is inverted from one position to another.

Referring to the embodiment and application of the invention as illustrated in Fig. 9, it will be seen that the hooks 7 have been adjusted in engagement with apertures relatively near the apertured flanges or ears 9, so as to extend the device longitudinally for engagement with the casing of a double window, and it will also be seen that the device illustrated in Fig. 11 is attached to the previously described device and to the middle post or partition of the window. This device is generally indicated by the numeral 21 and is formed of an apertured springy sheet-metal blank, the blank being somewhat similar to that from which the member 2 is formed, that is, it comprises two parallel arms and an intermediate spring element or plate which are joined to one another at angular portions indicated at 22. The arms of the member 21, being identical in form with the arms 12, need no detailed description, and are referred to by the numeral 12^a, the several pintle bearings and curtain-pole bearings being referred to by numerals indicating like elements, in Fig. 6, followed by the letter "a," as 16^a, 17^a, etc. However, the intermediate portion 23 is both structurally and functionally different from the intermediate portion 14 of the member 2, being curved or concavo-convexed from one to another of its ends 22, and being formed with a slot 24 having one end enlarged to permit the head of a nail or screw to be passed therethrough, the remaining portion of the aperture 24 being too narrow to permit the head of the fastening member to pass therethrough, and this enables the device to be removably secured to a headed fastening member without removing the latter. Moreover, as this member 21 is of springy sheet metal, its intermediate portion or securing portion 23 may be straightened by pressing the arms 12^a toward one another. When thus straightened, the aperture 24 may be passed onto and laterally of the headed fastening member such as indicated at 25 in Fig. 9, and its inherent spring action causes it to frictionally engage the head of the fastener 25 and also to frictionally engage with the post or partition of the window to which it is secured, so that this device automatically secures itself in

position on the window. Before thus securing the member 21 on the window, the spring 3 is passed through enlarged portions 18^b of the apertures 18^a, and now, when the device 21 is secured on the fastener 25 while the bars 1 are engaged with the window casing, the spring 3 prevents the member 21 from turning on its pivot. Moreover, when the shade-rollers are placed in their respective seats, as indicated at a—a in Fig. 9, they coat with the brackets 2 for preventing the member 21 from moving laterally with relation to the fastener 25.

In fitting up a triplex window, as indicated in Fig. 10, each of the two outer windows is provided with one of my complete single-window attachments, and a shade-roller or curtain-rod (such as indicated at b in Fig. 10) is supported by the arms 12, the pintles of this shade-roller being alined with those of the shade-rollers or curtain-rods a. This arrangement of shade-rollers is provided for by the duplex brackets 2, each arm of these brackets having the corresponding pintle bearings 16, 17 and 18 as described in the foregoing. Moreover, by this arrangement of two window attachments in connection with three windows or a triplex window, the arms 12 may combine for supporting a curtain rod c which extends from one to the other of the end brackets 2, although it is obvious that a shorter curtain-pole may be supported solely by the two inner brackets. The arrangement shown in Fig. 10 is also useful in connection with two windows, and for the purpose of explanation, it will be assumed that the middle window is not a window but a portion of wall between the two outer windows, and that this space between the windows is adapted to support a clothes hanger or a series of clothes hooks. It will be seen that a curtain suspended from a short pole supported on the two inner brackets 2 will hide and protect the clothing hung behind this curtain.

It is to be understood that the term curtain, as used in the claims should have its broadest definition, including what is ordinarily termed a window-shade, also that the term curtain-rod is used in its broadest sense and may include both what is ordinarily termed a curtain-pole and what is ordinarily termed a shade-roller.

Although I have described these embodiments of my invention specifically, it is not intended to limit this invention to these exact details of construction and arrangement, but changes may be made within the scope of the inventive ideas as implied and claimed.

What I claim as my invention is:

1. A curtain-supporting bracket consisting of sheet metal and being formed with substantially parallel arms, a springy

- clamping element between and united with said arms, apertured angular portions at the juncture of the clamping element with the arms, and a seat to receive and support 5 an end of a curtain pole, the apertures of said angular portion being adapted to receive a bar therethrough in such relation that said arms can coact with said clamping element in clamping said bar.
- 10 2. A curtain-supporting member formed integrally of a springy apertured sheet-metal blank and comprising two substantially parallel arms and a spring clamping element between said arms, two apertures 15 of the support being located at the meeting edges of said clamping element and arms and being adapted to receive a bar therethrough, two edges of said apertures being coöperative with the said spring clamping 20 element to clamp said bar, the other edges of the clamping element being inwardly recessed to weaken the spring element along its central line between said apertures.
- 25 3. A curtain-supporting bracket consisting of sheet metal and being formed with substantially parallel arms, a springy clamping element between and united with said arms, apertured angular portions at the junction of the clamping element with the 30 arms, and a pintle-seat in each of said arms to receive pintles of two separate shade rollers.
- 35 4. In a curtain support, the combination of a normally horizontal supporting structure attachable to a window, and a pair of brackets each mounted for horizontal adjustment on said structure, each of said brackets comprising two spaced arms and a springy clamping element, the latter being 40 between and united with ends of said arms and coöperative with these ends to clamp said supporting structure in different adjusted positions, said clamping element being movable out of its coöperative relation to said arms by movement of the latter toward one another, one arm of each bracket being formed with a curtain-rod bearing.
- 45 5. In a curtain support, the combination of a normally horizontal supporting structure attachable to a window, and a pair of brackets each mounted for horizontal adjustment on said structure, each of said brackets comprising two spaced arms and a springy clamping element, the latter being between 50 and united with ends of said arms and coöperative with these ends to clamp said supporting structure in different adjusted positions, said clamping element being movable out of its coöperative relation to said arms 55 by movement of the latter toward one another, each arm of each bracket being formed with a curtain-rod bearing, whereby a pair of these brackets can coact with another bracket or other brackets in supporting two 60 or more curtain-rods, substantially as shown.
6. In a curtain-rod support, a pair of bars each being attachable to a door or window and having one end provided with a laterally extending apertured ear, a helical spring extending through the apertured ears 70 of said bars and being secured to intermediate parts of said bars, and a pair of curtain-rod-brackets, mounted for horizontal adjustment on said bars respectively.
7. In a curtain-rod support, a pair of 75 bars each provided with a laterally extending hook and an apertured ear extending laterally from the side opposite to that from which the hook extends, a retractile spring extending through the apertured ears of said bars and being secured to an intermediate part of each bar and effective to draw the bars toward one another for holding said hooks in engagement with a door or window and also effective to keep the bars 80 alined with one another, and two curtain-rod-brackets mounted respectively on said bars.
8. In a curtain-rod support, a pair of 85 bars each provided with a laterally extending slotted hook and an apertured ear extending laterally from the side opposite to that from which the hook extends, a retractile spring extending through the apertured ears of said bars and being adjustably 90 secured to an intermediate part of said bar and effective to draw the bars toward one another for holding said hooks in engagement with a headed fastener or with the casing of a door or window and also effective to keep the bars alined with one another, and two curtain-rod-brackets mounted 95 respectively on said bars and being horizontally adjustable along said bars.
9. The combination of three shade-roller 100 brackets supported in alinement, each of these brackets comprising two spaced arms and a support-engaging element between said arms, and two shade-rollers having pintles, each arm of said brackets being 105 provided with a pintle-bearing in which a corresponding one of said pintles is seated.
10. The combination of two bars each having one end provided with attaching means to engage a door or window, the 110 other end being provided with an apertured laterally extending ear, a helical spring extending through the apertured ears of said bars and being secured to these bars and coöperative with said attaching means to secure said bars in engagement with the door or window that supports the bars and spring, a pair of curtain-rod-brackets each supported by one of said bars, and a two-115 armed curtain-rod-bracket provided with attaching means between its arms for engaging with the middle partition of a double window, each arm of said two-armed bracket being provided with a curtain-rod-seat and with an aperture through which said spring 120
- 125
- 130

extends in such relation that said two-armed bracket supports the middle part of said spring.

11. The combination of two shade-roller supports, and three shade-rollers, each of said shade-roller-supports comprising a bracket-supporting structure and two shade-roller-brackets, the latter being supported by said structure, each of two of said 10 brackets being provided with two spaced pintle-bearings, whereby the said two shade-roller-supports are effective to support the said three shade-rollers through the medium of their pintles.

15. 12. A curtain-rod-bracket formed of a springy sheet-metal blank and comprising two spaced arms and an attaching plate, the latter being centrally slotted for attachment to a headed fastener, the attaching plate 20 being concavo-convexed and having its convex surface facing toward the space between the distant ends of said arms so that the plate exerts a spring-pressure against the head of said headed fastener and against a 25 door or window which holds said fastener, each of said arms being provided with a curtain-rod-seat, said attaching plate being deflectable by an inward movement of said arms toward one another for the purpose of 30 releasing said attaching plate from the headed fastener, as described.

13. A curtain-rod-bracket formed of a springy sheet-metal blank and comprising two spaced arms and an attaching plate, the

latter being centrally slotted for attachment 35 to a headed fastener, the attaching plate being concavo-convexed and having its convex surface facing toward the space between the distant ends of said arms so that the plate exerts a spring-pressure against the 40 head of said headed fastener and against a door or window which holds said fastener, each of said arms being provided with a curtain-rod-seat, said arms being apertured 45 at points adjacent to said attaching plate to receive a supplementary support there-through.

14. A curtain-rod-bracket formed of a springy sheet-metal blank and comprising two spaced arms and an attaching plate, the 50 latter being centrally slotted for attachment to a headed fastener, the attaching plate being concavo-convexed and having its convex surface facing toward the space between the distant ends of said arms so that the 55 plate exerts a spring-pressure against the head of said headed fastener and against a door or window which holds said fastener, each of said arms being provided with a plurality of shade-roller-bearings of different sizes and located different distances 60 from said attaching plate, each of said arms also being formed with curtain-pole seats of different sizes.

In testimony whereof I have hereunto set 65 my hand.

GILBERT E. ALPHIN.
